US00D801298S

(12) **United States Design Patent** (10) Patent No.: **US D801,298 S**
(45) Date of Patent: **** Oct. 31, 2017**

(54) **IN-VEHICLE AUDIO PROCESSOR**

(71) Applicant: **CLARION CO., LTD.**, Saitama (JP)

(72) Inventor: **Keita Katsuno**, Matsudo (JP)

(73) Assignee: **CLARION CO., LTD.**, Saitama (JP)

(**) Term: **15 Years**

(21) Appl. No.: **29/556,445**

(22) Filed: **Mar. 1, 2016**

(30) **Foreign Application Priority Data**

Sep. 3, 2015 (JP) 2015-019586

(51) LOC (10) Cl. **14-03**

(52) U.S. Cl.

USPC **D14/157**; D14/217

(58) **Field of Classification Search**

USPC D14/157, 188-198, 217, 498-511;
455/344-346

See application file for complete search history.
